CLAIM

The ornamental design for a safety lock for windows, substantially as shown and described.

DESCRIPTION

FIG. 1 is a perspective view of a safety lock for windows showing our new design;

FIG. 2 is a view similar to FIG. 1 showing another position of the safety lock for windows;

FIG. 3 is a front view of the safety lock for windows;

FIG. 4 is a rear view of the safety lock for windows;

FIG. 5 is a top plan view of the safety lock for windows;

and

FIG. 6 is a bottom plan view of the safety lock for windows.

*Fig. 1.**Fig. 2.**Fig. 3.**Fig. 4.**Fig. 5.**Fig. 6.*
